UNITED STATES PATENT OFFICE.

JAMES H. MCKENDRICK, OF MEDIA, PENNSYLVANIA.

PAPER BAG.

1,134,341.

Specification of Letters Patent.

Patented Apr. 6, 1915.

Application filed June 18, 1914. Serial No. 845,993.

To all whom it may concern:

Be it known that I, JAMES H. MCKENDRICK, a citizen of the United States, residing at Media, county of Delaware, and State 5 of Pennsylvania, have invented a new and useful Improvement in Paper Bags, of which the following is a full, clear, and exact description, reference being had to the accompanying drawings, which form a part of 10 this specification.

The object of my invention, generally stated, is to provide a paper bag which, operating as a container or receptacle for merchandise, may be either carried by hand or 15 transported by parcel post.

More specifically, the object of my invention is to provide a bag of the character specified which may be made inexpensively, which may be readily grasped by the hand, 20 which may be securely closed, and which will not tend to tear with ordinarily careful usage even though loaded with bulky or heavy material.

A bag having certain characteristics of 25 the bag forming the subject matter of my present invention is set forth in the patent issued to me November 5, 1901, No. 685,789. A bag constructed in accordance with the specific embodiment of the invention of said 30 patent comprises a pair of wooden strips, extending entirely across the mouth of the bag in connection with a flap cut from the body and arranged to reinforce the strips. Such a bag is practicable and useful, but it 35 is somewhat expensive to manufacture and the bag tends to tear at the middle angle formed at the junction of the upper edges of the two folds of the end wall. Such a bag, therefore, does not meet all the conditions required to provide a bag that will 40 command a wide market. Chief among such conditions are that the bag shall be capable of being made cheaply enough to allow a merchant to give it away free with merchandise purchased, that it shall be capable 45 of securely holding the articles purchased, whether it be carried away or mailed, and that it shall be, in and of itself, on account of its capacity for re-use, an article of value 50 to the purchaser.

The present invention embodies certain features of the patented receptacle above specified but omits other features of such bag and at the same time exhibits special

features of novelty which enable it to meet 55 the requirements hereinbefore specified.

In the drawings, which show a preferred embodiment of my invention: Figure 1 is a perspective view of the bag with mouth open. Fig. 2 is a similar view of the bag 60 with mouth closed. Fig. 3 is a view of the blank from which the central reinforcing piece is formed. Fig. 4 is a partial detail view of same. Fig. 5 is a side elevation of the upper part of a modified form of bag. 65

The body of the bag may be made in any known manner. In the drawings I have shown a bag consisting of folds *a* forming the sides and folds *b* forming the bottom. The upper edges of the bag extend straight 70 and horizontal from end to end, although, if the adaptability for transportation through the mails is deemed of secondary importance, two triangular folds *c* may be formed from the opposite sides at each upper corner of the bag and the folds bent inwardly against each other, as shown in Figs. 1 and 2. If, however, the capacity for transportation is deemed of primary importance, these folds will not be formed, and in place 75 thereof strips *d*, shown in Fig. 5, will be applied to each side at each corner of the bag, each strip extending from the end edge along and adjacent to the upper edge of the bag toward the vertical center line of the 80 bag but terminating a considerable distance short of the center.

Between the strips *d*, or the folds *c*, dependent upon which construction is employed, extends along each side of the bag, 90 a reinforcing piece *e*, said reinforcing piece extending from the upper edge downward for a distance considerably greater than the width of the strips *d*. This reinforcing piece is made of paper that is heavier than 95 the paper of which the body of the bag is composed, and its upper edge is bent downwardly for a distance about equal to the width of a strip *d* to form a ply *f* and thence upwardly to form a ply *g*, the ply *g* extending 100 between the ply *f* and the body of the strip. The central part of the body of the bag is thus reinforced along its upper edge and for a substantial distance beneath its upper edge 105 and is trebly reinforced immediately adjacent to its upper edge, while between the ends of the bag and its central portion the upper edge of the bag is either not rein-

- forced, as is Figs. 1 and 2, or is provided with separate reinforcing strips, as in Fig. 5, either of which constructions permits the bag to bend between its ends and the specially reinforced central portion, thus avoiding the liability to tear at its extreme ends while permitting the sides of the bag to swell outwardly away from each other to afford a large carrying capacity for the bag.
- 10 Beneath the plies *f* and *g* of each reinforcing piece *e* is formed, through the body of the bag and the body of the piece *e*, a cut-out flap *h*. The two flaps may be bent outwardly in the same direction so that one underlies the other, thus affording a hand-hold for convenience in carrying.

While the reinforcing pieces *e* add somewhat to the expense of the bag, this expense is small compared to the expense of the construction shown in my said patent. Further, the expense of the reinforcing pieces would be more than counterbalanced by the extra amount of paper required to produce a plain paper bag of equal capacity; because 25 to produce such a bag, the same would have to be made considerably deeper so as to afford a length of paper at the top sufficiently great to allow the upper edge of the bag to be rolled up and grasped by the hand. It 30 will thus be appreciated that my improved paper bag is no more expensive than an ordinary plain paper bag of equal capacity, although its advantages over a plain paper bag are obvious.

35 Near the upper edge of the bag are provided two pairs of perforations *i*, the perforations extending through the specially reinforced part of the piece *e* near opposite ends thereof. Through these perforations 40 a cord may be passed to bring and secure together the upper edges of the bag.

When the construction shown in Fig. 5 is employed, there is formed a row of perforations *j* extending lengthwise of the strips *d* and the specially reinforced part of the piece *e*. Through these perforations may be passed a cord for securing together the upper edges of the bag throughout their length, thereby affording a perfectly secure 50 closure when the bag is employed for transporting merchandise by post, express or freight.

Having now fully described my invention, what I claim and desire to protect by 55 Letters Patent is:

1. A paper bag comprising a body portion the sides of which terminate at the upper edge of the bag, separate reinforcing pieces applied to opposite sides of the bag, along its upper edges, each reinforcing piece being substantially wider in the direction of its height than the distance from its lower edge to the upper edge of the bag, the part thereof that would otherwise extend above the upper edge of the bag being

folded upon itself to form a reinforcing member of special thickness, narrow relative to the total width of the reinforcing piece, extending along the upper edge of the bag, each reinforcing piece and special reinforcing member being of materially less length than the width of the bag and located centrally between the ends of the bag, and flaps cut from the body and reinforcing pieces beneath said members. 75

2. A paper bag comprising a body portion the sides of which terminate at the upper edge of the bag, separate reinforcing pieces applied to opposite sides of the bag, along its upper edges, each reinforcing piece being substantially wider in the direction of its height than the distance from its lower edge to the upper edge of the bag, the part thereof that would otherwise extend above the upper edge of the bag being of a material heavier than the material of the body of the bag and bent upon itself first outward and downward and thence inward and upward to form a reinforcing member of special thickness, narrow relative to the total width of the reinforcing piece, extending along the upper edge of the bag, each reinforcing piece and special reinforcing member being of materially less length than the width of the bag and located centrally between the ends of the bag, and flaps cut from the body and reinforcing pieces beneath said members. 85 95

3. A paper bag comprising a body portion the sides of which terminate at the upper edge of the bag, reinforcing pieces applied to opposite sides of the bag, each reinforcing piece terminating at its opposite ends a substantial distance from the ends of the bag and extending in the direction of its height from a substantial distance below the upper edge of the bag to its upper edge and thence bent upon itself for a distance substantially less than its height to form a relatively narrow reinforcing member of special thickness extending along the upper edge of the bag, and separate reinforcing strips applied to the sides of the bag along the upper edge thereof and terminating at the ends of the bag, there being a row of perforations extending along the reinforced upper edge of the bag. 105 110 115

4. A paper bag comprising a body portion the sides of which terminate at the upper edge of the bag, reinforcing pieces applied to opposite sides of the bag, each reinforcing piece terminating at its opposite ends a substantial distance from the ends of the bag and extending in the directions of its height from a substantial distance below the upper edge of the bag to its upper edge and thence bent upon itself for a distance substantially less than its height to form a relatively narrow reinforcing member of special thickness extending along the upper edge of 120 125 130

the bag, and separate reinforcing strips applied to the sides of the body adjacent to their upper edges and extending between the edges of the bag and the outer margins of the reinforcing pieces, there being a row of 5 perforations extending along both the reinforcing strips and the special reinforcing members.

In testimony of which invention, I have hereunto set my hand, at Philadelphia, on 10 this 16th day of June, 1914.

JAMES H. MCKENDRICK.
